UNITED STATES PATENT OFFICE.

JOSEPH SCHOENER, OF NEW YORK, N. Y.

CORSET-LOCK.

1,118,815.

Specification of Letters Patent.

Patented Nov. 24, 1914.

Application filed January 9, 1914. Serial No. 811,207.

To all whom it may concern:

Be it known that I, JOSEPH SCHOENER, a citizen of the United States and a resident of the city of New York, borough of Brooklyn, in the county of Kings and State of New York, have invented a new and Improved Corset-Lock, of which the following is a full, clear, and exact description.

My invention relates to means for locking 10 a corset.

The object thereof is to provide a simple, efficient, strong, positive and inexpensive device whereby a corset can be easily and quickly locked, which device will not accidentally unlock itself, and which will render the corset less cumbersome, as the number of securing means can be greatly reduced, which means, furthermore, when locked will stay in locked position and when 20 unlocked will remain so.

I attain the above object by providing a corset lock in which one of the corset steels has a plurality of spaced projections and the other, a plurality of lateral extensions similarly spaced, each of said extensions being adapted to engage the corresponding projection and maintain it in engagement by suitable means provided in each of the extensions and operable at the will of the 30 wearer.

The invention consists of the construction and combination of parts to be more fully described hereinafter and fully set forth in the claim.

Reference is to be had to the accompanying drawings forming a part of this specification, in which like characters indicate corresponding parts in all the views and in which:

Figure 1 is an elevation of the front of a corset provided with locking means embodying my invention; Fig. 2 is an enlarged front elevation of the device, the corset steels being shown uncovered and secured to each other; Fig. 3 is a similar view, partly in section, showing the detail of construction, the two corset steels being in unlocked position; Fig. 4 is a rear elevation of the device in locked position, partly in section, to show the detail of construction; Fig. 5 is a similar view showing the device in unlocked position; and Fig. 6 is a rear elevation of the extension with the locking means therein in unlocked position.

Referring to the drawings, 7 and 8 represent the corset steels, of which the steel 7

is provided with a plurality of lateral extensions 9 suitably spaced from each other and each having the shape of an elongated U, the extremities of which are secured to 60 said steel 7 by means of rivets 10, or any other convenient means, whereby the width between the sides 11 and 12 is equal to the thickness of the corset steel 7. Mounted to slide between the sides 11 and 12 of each 65 of the extensions 9 is a member 13, the sliding movement of which in said extension is controlled by a pin 14 which projects through a slot 15 provided in the side 11 of the extension. Said pin 14 is provided 70 with a head above the side 11 to facilitate the movement of said sliding member 13 within said extension 9. The sides 11 and 12 of each extension 9 are provided with alining apertures 16 which are adapted to 75 be engaged by corresponding projections 17 provided on the corset steel 8. That is to say, the projections 17 on the corset steel 8 are spaced similar to the extensions 9 on the corset steel 7 and, therefore, each extension 80 on the corresponding projection forms a unit of a locking device.

The sliding member 13 is provided with a slot 18, one end 19 of which slot is enlarged and adapted to register with the aperture 85 16 of the extension 9 (see Figs. 3 and 5). The sliding member 13 is adapted to engage the slot 20 provided in the projection 17 when said sliding member is moved from the position shown in Fig. 3 to the position 90 shown in Fig. 2, that is, when the unenlarged section of the slot 18 engages the projection 17, the engagement between the slot of the pin and the sliding member 13 being best shown in Fig. 4. When the sliding 95 member 13 is in position shown in Figs. 3, 5 or 6, the projection 17 can be easily inserted into the extension 9 or removed therefrom.

The side 12 of the extension 9 is provided 100 with a recess 22 into which projects a pin 23 carried by the sliding member 13. A resilient member 21 carried by the side 12 projects into said recess 22 and therein engages the pin 23 so that normally said 105 spring tends to force the sliding member 13 into the extension 9, that is, into locked position. The resilient member 21 has, adjacent its free end, a curved portion 24 into which the pin 23 snaps when the sliding 110 member 13 is moved to the unlocked position (see Fig. 5). The recess 22 in the side

12 of the extension 9 is exteriorly closed by a member 25 secured to the side 12 by the same rivets 10 which secure the extension to the corset steel 7, or by any other suitable means.

As shown in Fig. 1, the steels 7 and 8 are covered, as is customary, with the material of which the corset is made, so that the rivets 10 by which the extensions 9 are secured to the corset steel 7 are necessarily covered thereby and are not in the way of the locking means. The head of the pin 14 projects very little above the side 11 of the extension, and the accidental displacement of the same is reduced thereby to a minimum. Furthermore, the resilient member 21 tends to maintain it in locked position, in addition to gravity. But when said sliding member is placed in unlocked position, the resilient member maintains it in said position, as previously stated, and thus facilitates a quick removal of the corset without any interference between the locking parts carried by the corset steel, as generally occurs between the locking means of corsets in use at present.

Having thus described my invention, I claim as new and desire to secure by Letters Patent:

In a corset lock, a steel; a U-shaped mem-

ber secured by its extremities to said steel and forming a lateral extension therefrom; a second steel; a projection on said steel, said U-shaped member having alining apertures in the sides thereof adapted to receive said projections; a member mounted to slide between the sides of said U member; means for guiding said member in said U-shaped member, said sliding member having a slot adapted to engage said projection when said projection engages the U-shaped member, whereby the two steels are secured to each other, said U-shaped member having a recess in one of the sides thereof; a pin on said sliding member projecting into said recess; a resilient member in said recess engaging said sliding member and tending to force the said sliding member into the U-shaped member, said resilient member having a notch at the free end thereof adapted to engage said pin of the sliding member, whereby said sliding member is maintained in unlocked position.

In testimony whereof I have signed my name to this specification in the presence of two subscribing witnesses.

JOSEPH SCHOENER.
